UNITED STATES PATENT OFFICE

CECIL C. PARRISH, OF DONORA, PENNSYLVANIA

TILTABLE VESSEL

Application filed February 28, 1931. Serial No. 519,129.

This invention relates to a safety automatic leveling device for tilting vessels or furnaces and is particularly adapted for application to metal mixers used in the production of 5 Bessemer and open hearth steel.

When pouring from the usual type of metal mixer or furnace as heretofore constructed, should the tilting motors or mechanism refuse to function, due to power failure, for 10 example, or should the operator suddenly become incapacitated, the vessel would remain in a tilted position for a certain length of time until righted or until it could be placed in condition to be further tilted to resume the 15 pouring operation, and during this time the metal issuing from the pouring spout would freeze. In attempting to place the mixer in condition to resume pouring while the mixer was in a tilted position, the workmen were 20 placed in a hazardous position and in many instances serious accidents would occur as well as a loss of time and labor.

The present invention has been designed with a view toward eliminating the foregoing 25 hazards and losses by providing means which operates automatically to right or level the vessel or furnace the instant the tilting mechanism ceases to function due to causes over which the operator has no control, or should the operator suddenly become 30 incapacitated and release the controls. In its preferred form, the improved device utilizes a combination switch and drive-reversing mechanism including a counterweight which 35 is connected up and operates in conjunction with the tilting mechanism. It will be understood, however, that obvious modifications in structure and design may be adopted without departing from the scope of the invention 40 as defined by the specification and appended claims.

In the drawings:—

Figure 1 is a view in transverse vertical 45 section and elevation of a conventional type of metal mixer with the improved automatic leveling device operatively connected up therewith.

Figure 2 is a view in side elevation with the counterweight mechanism omitted.

Figure 3 is a diagrammatic representation

of an electrical circuit for the switch-operating mechanism.

The reference numeral 5 generally designates the mixer or vessel which, as shown, is of the conventional tilting type made up of 55 riveted steel plate to form an outer shell which is lined with silica or fire brick, molten iron being poured into the mixer through an opening 6 and poured therefrom through a spout opening 7. The vessel is supported on 60 base members 8 on which bearing rolls 9 are mounted, annular rails or tracks 10 being formed partially around the vessel and having movement on said rolls.

The vessel or mixer, as here shown, is tilted 65 by means of arms or levers 12 which are pivotally connected at one end to the rails or tracks 10 and at their opposite ends to guide blocks 13 adapted to travel in trackways 14, the blocks 13 being reciprocated by a threaded engagement with screws 15, which are mounted in bearings 16 and have secured on the ends thereof bevel gears 17. Extending longitudinally of the mixer on one side thereof is a shaft 18 which is flexibly coupled and provided with bevel pinions 19 adapted to mesh with the gears 17, power being applied to said shaft through the medium of one or more motors 20 supported on a base or bases 21 at one or both ends of the vessel or along 80 the length of said shaft.

The improved automatic levelling mechanism as shown in the present instance depends upon a counterweight 22 for overhauling or reversing the drive on the tilting 85 mechanism and righting the vessel, said weight being suspended from a pin or shaft 23 on which a sheave 24 is mounted. Above the sheave 24 is another sheave 25 which is supported from beams 26 by means of hanger brackets 27. The weight 22 may be guided by vertically extending columns or beams 28, and a bumper 29 and spring 30 are provided at the base of the structure to cushion the weight and mechanism against sudden 90 lowering movement.

A cable drum 31 is mounted at one side of the vessel or mixer on a countershaft 32 which is supported on bearing pedestals 33, said drum being provided with a gear 34 adapted 100

to mesh with a pinion 35 secured on the shaft 18. A cable 36 is attached at one end to the drum 31 and passes around guide sheaves 37 and 38 and sheaves 25 and 24.

It will be seen that when the shaft 18 is driven in one direction to tilt the mixer or vessel 5, the drum 31, which is geared to said shaft, is rotated and the counterweight 22 is raised, and as the vessel moves back to normal position, the weight is lowered, the vessel thus tilting against the resistance offered by said weight.

The shaft 18 has mounted in cooperative relation therewith a brake 39 which is preferably of the electrically applied and spring released type as shown, this brake and the tilting mechanism being controlled through the electrical circuit illustrated in Fig. 3.

Referring to this figure, the line wires are indicated at L_1 and L_2 , and the wires which lead to the control feeders or the tilting motor supply are indicated at 40 and 40', a magnetic switch or electrical contactor 41 being interposed in this circuit so that the latter may be closed when desired and the motor circuit energized ready for operation.

The switch and magnetic brake circuit is connected to the line by wires 42 and 42' and the wires which supply the magnetic brake are indicated at 43 and 43', a magnetic switch or contactor being also interposed in this circuit at 44. The wires which lead to the contactor 41 are indicated at 45 and 45', and this circuit is normally held open by a master switch 46, and the wires which lead to the contactor 44 are indicated at 47 and 47' and likewise this latter circuit is normally held open by a master switch 48.

It will be seen that when the master switch 46 is closed, the contactor 41 becomes energized and the circuit which supplies the tilting motors is closed, and when master switch 48 is closed, the contactor 44 becomes energized and the magnetic brake circuit is closed.

Master switches 46 and 48 may be of any standard type which are held in contact by the operator and automatically thrown to the "off" position when released. These switches are shown diagrammatically in Figure 3. The switch 46 is shown as a foot pedal switch with a spring return, and the switch 48 is shown as a hand operated spring return switch.

The operation of the mechanism is as follows:

Assuming the vessel or mixer 5 to be in a level position ready for pouring, the operator steps on a foot pedal or actuates in any suitable manner the master switch 46 and the magnetic switch or contactor 41 closes the circuit 40, 40', which supplies the control feeders or tilting motors. The regular controllers for the tilting motors are then operated and the vessel or mixer 5 is tilted to

pouring position, the revolving cable drum 41 raising counterweight 22.

When the vessel reaches the desired pouring position, the operator moves the controls for the tilting motors to neutral position and actuates master switch 48, thus energizing contactor 44 and closing the brake circuit 43, 43' and setting the brake 39, thereby preventing the counterweight 22 from overhauling the drum 31 and leveling the vessel before pouring is completed. When pouring is completed, the operator releases master switch 48, deenergizing the brake circuit and releasing brake 39. The counterweight 22 then overhauls the tilting mechanism and returns the vessel to a level position.

In case of power failure or should the operator suddenly become incapacitated while the vessel is in a pouring or semipouring position, all circuits automatically open and the counterweight returns the vessel to a level position.

What I claim as new is:

1. The combination with a tilttable vessel, of tilting mechanism therefor, means for operating said mechanism to tilt the vessel, and means for automatically returning the vessel to a level position upon failure of said operating means.

2. The combination with a tilttable vessel, of tilting mechanism therefor, means for operating said mechanism to tilt the vessel, and interposed means which acts against tilting movement of said vessel, the action thereof being such as to overhaul said tilting mechanism when the latter is rendered inoperative and return the vessel to a level position.

3. The combination with a tilttable vessel, of tilting mechanism therefor, positively applied controls for transmitting power to said tilting mechanism, and means for returning said vessel to a level position upon release of said controls.

4. The combination with a tilttable vessel, of electrically operated tilting mechanism therefor, positively applied controls for transmitting current to said operating mechanism, and means for returning said vessel to a level position upon release of said controls.

5. The combination with a tilttable pouring vessel, of electrically operated tilting mechanism therefor, the electric circuit being normally open, positively applied switches for closing the circuit and tilting said vessel to a pouring position, and means for returning said vessel to a level position upon interruption to said circuit.

6. The combination with a tilttable vessel, of tilting mechanism therefor, a brake for holding said vessel in tilted position, and means for returning said vessel to a level position upon release of said brake.

7. The combination with a tilttable vessel, of motor-driven tilting mechanism therefor, a brake for holding said vessel in a tilted posi-

tion, an electrical circuit for transmitting power to at least one motor energized thereby for driving said mechanism and for setting said brake, positively applied switches for closing said circuit, and a means for returning said vessel to a level position when said circuit is opened and said brake is released.

8. The combination with a tiltable vessel, of motor-driven tilting mechanism therefor, an electrically operated brake for holding said vessel in tilted position, an electric circuit for transmitting power to a motor energized thereby for driving said mechanism and setting said brake, magnetic contactors interposed in said circuit, positively applied switches for energizing said contactors and closing said circuit, and means for reversing the drive of said tilting mechanism when the switches are released and the circuit opened.

9. The combination with a tiltable vessel, of tilting mechanism therefor, means for operating said mechanism, and a counterweight for overhauling said tilting mechanism when the latter is rendered inoperative and returning the vessel to a level position.

10. The combination with a tiltable vessel, of tilting mechanism therefor including a drive shaft, means for driving said shaft in one direction to tilt the vessel, and means for applying a reverse drive to said shaft when the tilting drive is rendered inoperative.

11. The combination with a tiltable vessel, of tilting mechanism therefor including a drive shaft, means for driving said shaft in one direction to tilt the vessel, a cable drum geared to said shaft, and a counterweight attached to said cable for reversing the drive on said shaft when the tilting drive is rendered inoperative.

12. The combination with a tilting type molten metal vessel, of means for tilting said vessel to discharge the metal, said means including a shaft and an electric motor for operating said shaft, an electrically energized brake for holding said vessel in tilted position, and counterweight means for cooperating with said shaft for automatically returning the vessel to level position upon the deenergization of said motor and said brake.

13. The combination with a tilting type molten metal vessel, of means for tilting said vessel to discharge the metal, said means including a shaft and an electric motor for operating said shaft, an electrically energized brake for holding said vessel in tilted position, a drum on said shaft, a counterweight, a cable connected to said drum and said counterweight, said drum being rotatable to take up said cable and lift said counterweight when said shaft is operated to tilt said vessel, and said counterweight being adapted to automatically lower and return said vessel to level position upon the deenergization of said motor and said brake.

14. The combination with a tilting type

molten metal container, of means for tilting said vessel, and a counterweight for returning said vessel to level position.

15. The combination with a tilting type molten metal container, of means for tilting said vessel, and a vertical lift counterweight for returning said vessel to level position.

16. The combination with a tilting type molten metal container, of electrically operated means for tilting said container, a vertical lift counterweight for returning said vessel to level position when said tilting means is deenergized, said tilting means lifting said counterweight as said container is tilted.

17. The combination with a tilting molten metal container, of means for tilting said container including a power shaft, an electric motor for operating said shaft, an electrically energized brake for holding said container in tilted position, a vertical lift counterweight adapted to return said container to level position upon deenergization of said motor and said brake, and means operable by said power shaft for lifting said counterweight when said container is tilted.

18. The combination with a tilting molten metal container, of means for tilting said container including a power shaft, an electric motor for operating said shaft, an electrically energized brake for holding said container in tilted position, a vertical lift counterweight adapted to return said container to level position upon deenergization of said motor and said brake, a drum on said power shaft, and a cable connected to the drum and the counterweight, said drum being adapted to take up the cable and lift the counterweight when said container is tilted.

In testimony whereof, I have hereunto set my hand.

CECIL C. PARRISH.
